UNITED STATES PATENT OFFICE.

WILLIAM S. HUGHES, OF LONG ISLAND CITY, NEW YORK.

SLIDE-VALVE.

SPECIFICATION forming part of Letters Patent No. 242,929, dated June 14, 1881.

Application filed April 27, 1881. (No model.)

To all whom it may concern:

Be it known that I, WILLIAM S. HUGHES, of Long Island City, in the county of Queens and State of New York, have invented a new and Improved Slide-Valve, of which the following is a full, clear, and exact description.

The main object of this invention is to reduce or prevent the noise made by exhaust steam of engines, which has heretofore been attempted by the use of muffles and similar devices. With the ordinary link-motion and slide-valve used on locomotives the exhaust-edge of the valve must be moved the length of lap and lead before the piston receives steam from the direction in which it has been moving. In other words, the exhaust-opening begins before the piston finishes its stroke, and before the steam has fully expanded. The exhaust being also opened suddenly by the quick movement of the eccentric, a wasteful and disagreeable explosion of steam from the cylinder takes place. To remove this difficulty I have heretofore combined devices with the valve-cavity for obtaining a gradually-increasing opening, so that the exhaust previous to the completion of the piston-stroke is limited, and the exhaust-steam, instead of being allowed to explode, is gradually released, and without back-pressure.

The present invention is a variation of the invention shown in an application for Letters Patent heretofore made by me; and it consists in a valve having the sides of its exhaust-cavity graduated to give an opening gradually increasing in depth, in contradistinction to devices upon the face of the valve that cut off the opening more or less.

In the accompanying drawings, Figure 1 is a face view of a slide-valve embodying my invention, and Fig. 2 is a cross-section of the same.

Similar letters of reference indicate corresponding parts.

A is the slide-valve, having exhaust-cavity *a* on the under side. 45

B is the valve-seat, having steam-ports *b b* and exhaust-port *c*, as usual.

The sides of the exhaust-cavity *a* are made in step-like form, so that the depth increases as the valve moves forward, thereby giving an enlarged space for exhaust. The first opening being small and indirect, the exhaust-steam is baffled and detained, and the exhaust, instead of being an explosion, becomes an almost noiseless passage of steam to the exhaust-port and smoke-stack. There will be no back-pressure, for the reason that the first outlet of exhaust-steam takes place before the live-steam ports are opened, and the exhaust is fully open when the piston commences its return-stroke. 55 60

In Fig. 2 a perforated diaphragm or partition, *d*, is shown as fitted in the exhaust-cavity, for the purpose of dividing the exhaust-steam after it has entered the cavity. This partition may be dispensed with. 65

The construction may be modified to obtain regulation of the exhaust-opening, and indirect passages for the steam by variations in depth.

Having thus described my invention, I claim as new and desire to secure by Letters Patent— 70

1. A slide-valve having its exhaust-cavity *a* formed with sides graduated in depth, whereby an exhaust-opening gradually increasing in depth from the edge is obtained, substantially 75 as shown and described.

2. The slide-valve having the sides of its exhaust-passage made in step-like form, in combination with the perforated partition *d* therein, substantially as and for the purpose set forth. 80

WILLIAM S. HUGHES.
